United States Patent Office

Des. 208,628

Patented Sept. 19, 1967

208,628

PANEL UNIT FOR A ROOM DIVIDER OR SIMILAR ARTICLE

Jerome S. Smith, 3750 N. Lake Shore Drive,
Chicago, Ill. 60613

Filed Dec. 29, 1966, Ser. No. 5,218

Term of patent 14 years

(Cl. D13—1)

FIG. 1 is a front elevational view of a panel unit for a room divider or similar article embodying my new design;

FIG. 2 is a side elevation view;

FIG. 3 is a top plan view;

FIG. 4 is a bottom plan view; and

FIG. 5 is a sectional view taken on the plane of line 5—5 in FIG. 4 of the drawings and viewed in the direction indicated.

The side not shown is substantially the same as the one shown.

I claim:

The ornamental design for a panel unit for a room divider or similar article, substantially as shown and described.
